DRAWER CABINET WITH EJECTING AND
ADJUSTING MEANS

Carl Anton Tietje, Montclair, N. J.

Application February 8, 1945, Serial No. 576,738

3 Claims. (Cl. 312—149)

1

The invention relates to a drawer cabinet construction.

In drawer cabinets it has heretofore been customary to provide various devices for opening or closing the drawers which usually involve a handle that might have been a member projecting from the front, a pivoted bail or other knob-like projection from the front of the drawer that could be conveniently grasped in the hand of the person desiring to secure access to the 10 drawer.

In the design of furniture and particularly of modern furniture as well as in other instances it may and frequently is desirable in order to maintain the lines of design to avoid the use of knobs, bails or other handles. In the past it has been necessary to provide some type of device to be grasped but all such devices have affected the general appearance of the cabinet.

This invention seeks to provide in a drawer cabinet drawers under the control of the operator which may be projected from the cabinet without the use of any knob or other projection.

The invention seeks to provide further a cabinet construction wherein there may be a plurality of drawers free from any type of handle or knob for withdrawing the drawer.

More particularly, the invention provides in a drawer cabinet having a plurality of drawers a construction whereby the drawers are arranged in pairs so that when one drawer of a pair is moved inwardly another drawer is ejected.

Also provided by the invention are means to realign the drawers after operation to eject a selected drawer.

These and other objects which will be apparent from the sequent description are all embraced within the invention as hereinafter more specifically described and as set forth in the appended claims.

The invention is described with reference to certain preferred embodiments specifically illustrated in the accompanying drawings wherein:

Figure 1 is a view in front elevation with parts broken away showing a drawer cabinet;

Figure 2 is a view in section along the lines 2—2 of Figure 1;

Figure 3 is a view in section of an impositive lock; and,

Figure 4 is a view in section along the lines 4—4 of Figure 1.

Referring to Figure 1 there is shown a drawer cabinet 2 provided with a conventional top 4 and a plurality of drawers including a pair of drawers 6 and 8 arranged side by side, another similar pair of drawers 10 and 12 which drawers 6, 8, 10 and 12 are each of substantially half the width of the cabinet. There are also shown two full-length drawers 14 and 16.

The individual drawers have generally conven-

2

tional construction with front walls 18 which as shown in Figure 2 may be aligned with the cabinet front wall 20. Suitable end guides and center guides 22 may be provided as in usual drawer cabinet construction. The cabinet front wall 20 may provide drawer separating strips 24 or the drawers may be so arranged that their respective fronts 18 are adjacent each other or adjacent another drawer.

In accord with this invention means are provided whereby the drawers are arranged in operating pairs which pair arrangement may be side by side or one above the other. As illustrated, the pairs are adjacent although the invention could be applied to pairing drawers which were not directly adjacent.

Referring to Figure 2 the two full-length drawers 14 and 16 which are shown as near the bottom of the cabinet are each provided with a suitable back wall 26. The rear wall 28 of the cabinet or other member at the rear of the cabinet such as a portion of the frame on which the drawer rests may serve as a mount for a rocker arm 30. The rocker arm 30 is mounted in a bracket member 32 which in turn is mounted as above described at the rear of the cabinet. A spring 34 is also mounted in connection with the bracket member so that normally the rocker arm 30 will be held in what may be termed a neutral position. In this position the ends 36 of the rocker arm 30 will each engage the rear walls 26 of the respective drawers 14 and 16 when the front walls 18 of the cabinet 2. This is the normal position for the drawers.

When it is desired to withdraw a drawer as, for example, the drawer 14, the drawer 16 is pushed into the cabinet to the position shown in dotted lines in Figure 2 with the result that the rear wall 26 of the drawer 16 engages the lower end 36 of the rocker arm 30 pivoting it about its axis 38 and forcing the other end 36 of the rocker arm 30 against the rear wall 26 of the drawer 14 thereby ejecting the drawer to the position shown in dotted lines whereby the front wall 18 of the drawer 14 is ejected beyond the front wall 20 of the cabinet 2. In this position the drawer may be conveniently pulled out to any extent desired by grasping a cut-away portion 40 in the lower rear of the front wall 18. The drawer might be grasped from another edge, either a side or top edge of the front wall or the degree of ejection might be such that no special provision would be necessary.

The spring 34 may, if desired, be of such strength that when the operator releases the drawer 16 which has been pushed in, that drawer will be restored to its normal position with its front 18 flush with the front 20 of the cabinet 2 under the action of the spring 34. In any case

where the spring 34 is not sufficient to accomplish this, the drawer 16 would be restored to its proper position upon pushing the drawer 14 back into the cabinet after the articles to be removed or placed in the drawer had been so arranged.

In order to insure accurate aligning of the fronts 18 of the respective drawers with the wall 20 it may be desirable to provide means such as a latch or an impositive lock 42 illustrated in greater detail in Figure 3. As therein shown it comprises a ball 44 in a cylindrical chamber 46 held against lips 48 by a spring 50. This portion of the latch may be mounted in the strip 24 or other portion of the front 20 of the cabinet 2. Front 18 of a drawer may be provided with a member 52 with a notch 54 into which the ball 44 may fall when the front 18 of the drawer and the front 20 of the cabinet 2 are in alignment.

In Figure 4 is illustrated a suitable arrangement for a pair of adjacent half drawers such as the drawers 10 and 12. In this case a rocker arm 56 may be conveniently mounted on a longitudinal board 58 adjacent the rear of the cabinet 2 by a pivoting bolt or the like 60. The ends 62, 64 of the rocker arm 56 engage the rear walls of drawers 10 and 12, respectively, and spring 66 engages the rear portion of the rocker arm preferably adjacent the ends thereof. It will be recognized that instead of a leaf spring there could be provided coil tension or compression springs suitably mounted to accomplish a similar purpose.

In Figure 4 there is illustrated the position of the drawers after the operator had pushed drawer 12 into the cabinet to eject drawer 10. In so doing the drawer 10 and rocker arm 56 had assumed the position shown in dotted lines but when the operator released the drawer 12, the action of the spring 66 restored the drawer 18 to proper alignment while the drawer 10 stayed in partially ejected position as shown in dotted lines.

The rocker arm operating mechanism has been illustrated and described as mounted at the rear of the drawers but it will be evident that other mounting positions with cooperating mechanisms may be substituted. Instead of a rocker arm or other lever system the invention might be carried out by the use of cables or ropes together with suitable weights and pulleys.

While the invention has been described with respect to certain preferred embodiments, these are to be considered illustrative of the invention which is particularly set forth in the appended claims.

I claim:

1. In a cabinet having a wall with drawer openings, a pair of drawers therein, each drawer having a front wall, means mounting said drawers for movement through said openings in said cabinet wall into and out of said cabinet, releasable latching means to hold each drawer front wall in normal position with respect to said cabinet wall; said mounting means and releasable latching means permitting movement of each entire drawer into the cabinet beyond the wall of the cabinet, lever means within said cabinet engaging a portion of each of said pair of drawers, said lever means being so arranged that when one of said pair of drawers is pushed into said cabinet beyond the wall thereof the other of said drawers is ejected therefrom, and spring means to restore either drawer to normal position where it is held by said releasable latching means when

said drawer is released after it has been pushed into said cabinet, each said releasable latching means comprising cooperating elements which automatically hold the front wall of a drawer in the plane of the cabinet wall when the drawer is brought to this position by the action of the restoring spring yet releases the drawer for movement upon the application of greater force to the drawer.

10 2. In a cabinet having a wall with drawer openings, a pair of drawers therein, each drawer having a front wall, latching means for releasably holding the front wall of each drawer in normal position in alignment with the wall of said cabinet, means mounting said drawers for movement through said openings in said cabinet wall into and out of said cabinet, said mounting means and latching means permitting movement of each entire drawer into the cabinet beyond the wall of the cabinet, lever means within said cabinet engaging a portion of each of said pair of drawers, said lever means being so arranged that when one of said two drawers is pushed into said cabinet beyond the wall thereof the other of said drawers is ejected therefrom, and spring means to restore either drawer to normal position where it is held by said latching means when said drawer is released after it has been pushed into said cabinet, each said releasable latching means comprising cooperating elements which automatically hold the front wall of a drawer in the plane of the cabinet wall when the drawer is brought to this position by the action of the restoring spring yet releases the drawer for movement upon the application of greater force to the drawer.

3. In a cabinet having a wall with drawer openings, a pair of drawers therein, each drawer having a front wall, means mounting said drawers for movement through said openings in said cabinet wall into and out of said cabinet, releasable latching means to hold said drawers with their front walls in normal position in alignment with the wall of said cabinet, said mounting means and releasable latching means permitting movement of said drawers into the cabinet until the drawer front wall is beyond the wall of the cabinet, means actuated by the movement of one drawer into the cabinet to eject the other drawer so that its front wall is outside of the wall of the cabinet and spring means to restore said first mentioned drawer to its normal position where it is held by said releasable latching means with its front wall in alignment with the wall of the cabinet, each said releasable latching means comprising cooperating elements which automatically hold the front wall of a drawer in the plane of the cabinet wall when the drawer is brought to this position by the action of the restoring spring yet releases the drawer for movement upon the application of greater force to the drawer.

CARL ANTON TIETJE.
